UNITED STATES PATENT OFFICE.

ARTHUR C. EASTWOOD, OF CLEVELAND, OHIO.

PROTECTIVE DEVICE FOR ELECTRIC CIRCUITS.

No. 922,464.

Specification of Letters Patent.

Patented May 25, 1909.

Application filed November 23, 1908. Serial No. 463,988.

To all whom it may concern:

Be it known that I, ARTHUR C. EASTWOOD, a citizen of the United States, residing at Cleveland, in the county of Cuyahoga and State of Ohio, have invented or discovered new and useful Improvements in Protective Devices for Electric Circuits, of which the following is a specification.

My invention relates to new and useful combinations of devices for the protection of electric circuits, particularly electrical circuits containing the windings of an electric motor.

The objects of my invention are: 1st. To produce a simple and reliable combination of parts which will automatically open an electric circuit upon the occurrence of no voltage or of an abnormally low voltage and will not again permit the closing of the circuit until the requisite amount of resistance has been again included therein. 2nd. To provide an arrangement of parts which will automatically open the circuit in case of an abnormal flow of current therein and which will not again permit the closing of the circuit until the requisite resistance has been again reinserted in the circuit. 3rd. To provide means whereby the circuit may be readily opened from a distance with very simple and inexpensive additions to the apparatus.

The accompanying drawing illustrates diagrammatically my invention applied to a motor starter or speed controller used in connection with a compound wound motor.

In this drawing *s* is a knife switch connected to a source of current supply.

C is the starter or controlling device comprising an arm *A* carrying a contact brush *a* adapted to span two sets of concentrically arranged segments. The segments 1 to 12, inclusive, of the outer group are connected to various points in the bank of resistance *R*. The inner segment 13 is connected to one side of a knife switch *s* through the wire 16. The shorter inner segment 14 is electrically connected to the inner segment 13, this shorter segment being added for the sake of cheaper renewal when the contact becomes roughened through the action of the arc which inevitably occurs when the circuit is opened. The wire 16 is connected to the segment 13 through the winding of a blow-out coil *B*, the magnetic field set up by this blow-out coil being effective in disrupting the arcs formed when the circuit is opened

at the contacts of the switch. The lowermost segments *a'* of the outer group are dead segments, that is, they are not connected in an electric circuit. Contact segment 12 is connected through wire 17 to the series field *F* of the motor which in turn is shown in series with the winding *D* of the brake *d* designed to be released by means of a series wound magnet. The other end of this brake winding is connected to the armature *G* through the wire 18 and the other end of the armature connects through the wire 19 with the winding of an overload coil or relay *O* which in turn is connected to contact *s²* of the magnetically-closed switch *S*, the other main contact *s'* of which is connected through the wire 15 to the negative side of the knife switch *s*. It will, therefore, be seen that the contacts *s'* and *s²* of the magnetically-closed switch *S* are in series with the main circuit and this main circuit cannot be established until switch *S* is closed. The switch *S* is designed to open through the action of gravity or a combination of gravity and the spring *v* when its coil is deenergized or partially deenergized through an abnormal drop in voltage.

Assuming the switch *S* to be closed and the arm *A* of the controller *C* to be so moved that the brush *a* spans contacts 1 and 13, the main circuit will then be as follows: from the plus side of the switch *s*, through the wire 16, the blow-out coil *B*, the contact 13, the brush *a*, contact 1, all of the resistance *R*, the wire 17, the series field *F* of the motor, the series winding *D* of the brake, the wire 18, the armature *G* of the motor, the wire 19, the winding of the relay *O*, the contacts *s²* and *s'* of the switch *S*, and the wire 15 to the negative side of switch *s*, thus completing the circuit. The motor will then run at minimum speed. This speed will be gradually increased, if the arm *A* be advanced toward the full-on position until when the contact 12 is reached, the resistance *R* will all be cut out and the motor should operate at full speed. If while the motor is running, the voltage of the circuit should fail or should become abnormally low, the switch *S* will, as I will presently show, automatically open, the arm *A* of the controller *C* remaining in the position in which it had been previously left. Should now the voltage of the circuit be suddenly reestablished, the switch *S* will not at once close and in fact, cannot be closed until the arm *A* is brought to the off-position

so that all of the resistance R must be in the motor circuit when the switch S closes. It will be seen that one end of the winding w of switch S is connected through the wire 26, the contacts of the relay O and the wire 27 to contact 13 of the controller C . The switch S carries an auxiliary contact comprised by a disk or metallic bridging member T which connects together the stationary contacts t' , t^2 , t^3 when the switch S is open. The remaining end of the winding w of switch S is connected to the auxiliary contact t' , which is connected to the auxiliary contact t^2 , a resistance shown in the form of an incandescent lamp L being included between the contacts t' and t^2 . The contact t^2 is connected to the wire 23 which includes the additional resistance r , the wire 23 being connected by means of the switch h to the wire 22 leading to the wire 15 or the negative side of the switch s . The contact t^3 is connected through the wire 25 to the last contact 12 of the outer group of contacts of the controller C .

With the arm A of the controller C in any but the off-position, it will be seen that the effect is to connect both ends of the winding of the switch S to the same side of the circuit. No current can then flow through the winding of the switch S and the switch will not close. Following out these connections it will be seen that one end of the winding of the switch S is connected through the wire 26, the contacts of relay O and the wire 27 to the contact 13 which in turn is connected to the positive main through the blow-out coil B and the wire 16. The other end of the winding of coil S will also be connected to the positive main through the contact t' , the bridging member T , the contact t^2 , the wire 25, which is also connected to the positive main through the brush s , the contact 13, the winding of the blow-out coil B and the wire 16, when the arm of the controller is in any but the off-position. When the arm A is returned to the off-position, current then flows through the winding of the switch S as follows: from the positive side of the switch s , through the wire 16, the winding of the blow-out coil B , the contact 13, the wire 27, the contacts of the relay O , the wire 26, the winding w of the switch S , the auxiliary contact t' , the auxiliary contact t^2 , the resistance r , the wire 23, the switch h (assuming the switch h to be closed) and the wire 22 to the negative side of the switch s . This completes the circuit through the winding of the switch S and causes the switch to close. The motor may then be safely started as before by advancing the arm of the controller C so as to cut out the resistance R gradually. In case the arm of the controller should be advanced too rapidly so as to cause the motor to draw excessive current, or in case the motor should be over-loaded from any other cause, the relay O ,

the winding of which carries the full motor current, will raise its plunger, thus separating the auxiliary contacts t' . It will be seen that this interrupts the circuit of the winding of the switch S since one end of the winding 70 will be thereby disconnected from the wire 27, the contact 13 and the wire 16, through which it is normally connected to the positive side of the switch s . The switch S will then open and cannot again be closed until the arm A is again returned to the off-position, at which time the switch S will automatically close and the motor may be again started in the usual way. It will be seen also that the switch h is in the circuit of the winding 80 of the switch S , so that, if at any time the switch h is opened, the switch S will open thus opening the main motor circuit. Even if the switch h be closed, the arm A of the controller C must be returned to the off-position 85 before switch S can again close. The switch h can be placed at any desired distance from the motor and controller and, of course, a number of such switches can be connected in series so that the motor can be readily 90 stopped from a number of different points. Since the switch h and connecting wires leading to it have to carry only the very small currents required by the winding of the switch S , such switches may be installed in 95 desired places and in the most convenient number with very little addition to the cost of installation.

It is to be observed that the arrangement requires no additional or special contacts to the controlling switch C in view of which the safety features embodied in my invention may be readily applied to existing controlling switches not specifically designed with such protective features in view.

It will be understood that my invention embodies means for automatically opening the motor circuit in cases of under-voltage, no voltages, overload and also from a distance by the manual opening of a switch and that, when the circuit is opened under any of these conditions, the circuit is held open until all of the starting resistance is inserted in the circuit by moving the arm A of the controller C to the off-position, at which time the 110 magnetically operated switch automatically 115 closes.

I claim—

1. In combination an electric motor, a controlling switch and a magnetically-closed main switch in the circuit of said motor, a magnetizing winding for said main switch, and means for short-circuiting said magnetizing winding when said main switch is open and said controlling switch is in any but the off-position.

2. In combination an electric motor, a controlling switch and a magnetically closed main switch in the circuit of said motor, a magnetizing winding for said main switch,

and means for short circuiting said magnetizing winding when said main switch is open and said controlling switch is in any but the starting position, the short circuit around said magnetizing winding being opened when the controlling switch is brought to the off-position.

3. In combination a controlling switch, a magnetically closed switch having its contacts in the main circuit controlled by said controlling switch, the winding of said magnetically-closed switch being shunted through the contacts of said controlling switch when said magnetically-closed switch is open and the controlling switch is in any but the off-position.

4. In combination a controlling switch, a magnetically-closed switch having its main contacts in the circuit governed by said controlling switch, a winding for said magnetically-closed switch, one end of said winding being connected to the line contact of said controlling switch, the other end of said winding being connected to the other side of the line through a resistance and an auxiliary switch carried by said magnetically-closed switch and closed when said magnetic switch is open, the contacts of said auxiliary switch connecting the second end of the winding of said magnetically-closed switch to the same side of the line to which the other end of said winding is connected so long as the controlling switch is in any but the off-position.

5. In combination a controlling switch for an electric circuit, a magnetically-closed

main switch having its main contacts in the circuit to be controlled, a magnetizing winding for closing said main switch, connections between the ends of said magnetizing winding and the contacts of said controlling switch whereby both ends of said winding are connected to the same side of the supply circuit when the controlling switch is in any but the off-position and said main switch is open, and a relay having its winding in the circuit to be controlled and contacts in the circuit of the winding of said main switch.

6. In combination a controlling switch for an electric circuit, a magnetically-closed main switch having its main contacts in the circuit to be controlled, a magnetizing winding for closing said main switch, connections between the ends of said magnetizing winding and the contacts of said controlling switch whereby both ends of said winding are connected to the same side of the supply circuit when the controlling switch is in any but the off-position and said main switch is open, a relay having its winding in the circuit to be controlled and contacts in the circuit of the winding of said main switch, and a manually-operated switch also in the circuit of the magnetizing winding of said main switch.

Signed at Cleveland, Ohio, this 20th day of November, 1908.

ARTHUR C. EASTWOOD.
